UNITED STATES PATENT OFFICE

166,591

WEED CUTTER

John D. Casey, Medina, N. Y.

Application March 14, 1951, Serial No. 14,492

Term of patent 14 years

(Cl. D40—1)

To all whom it may concern:

Be it known that I, John D. Casey, a citizen of the United States, residing at Medina, in the county of Orleans and State of New York, have invented a new, original, and ornamental Design for a Weed Cutter, of which the following is a specification, reference being had to the accompanying drawing, forming part thereof.

I claim:

The ornamental design for a weed cutter, as shown.

JOHN D. CASEY.
